UNITED STATES PATENT OFFICE.

ABRAHAM KYDLAND, OF TELSTAD, MONTANA.

HORSE-DETACHER.

1,192,212.

Specification of Letters Patent. Patented July 25, 1916.

Application filed January 27, 1916. Serial No. 74,702.

To all whom it may concern:

Be it known that I, ABRAHAM KYDLAND, a citizen of the United States, residing at Telstad, in the county of Hill and State of Montana, have invented certain new and useful Improvements in Horse-Detachers, of which the following is a specification, reference being had to the accompanying drawings.

0 This invention relates to horse detachers, and the general object of the invention is the provision in connection with a doubletree of very simple means for detaching the traces from the doubletree in case of a run-
away.

A further object of the invention is the provision of means for this purpose including spring retracted trace-engaging members which are ordinarily held in a trace engag-
ing position against the tension of the springs but which when released will permit the springs to retract the trace-engaging members and release the horses.

A great many horse detaching devices are of complicated construction and partly or entirely mounted upon the wagon body, and another object of my invention is to provide a device which is not mounted upon the wagon body but which is in the form of a doubletree adapted to be mounted upon any tongue.

Other objects will appear in the course of the following description.

An embodiment of my invention is illustrated in the accompanying drawings, wherein:

Figure 1 is a plan view of my improvement applied to a tongue; Fig. 2 is an enlarged view showing one of the swingletrees in section; Fig. 3 is a section on the line 3—3 of Fig. 1; Fig. 4 is a section on the line 4—4 of Fig. 1; Fig. 5 is a perspective detail view of the means for engaging the trace-locking bolts with the pivot bolt.

Referring to these figures, 10 designates a wagon tongue connected to the wagon in any suitable manner and upon which is mounted the evener bar 11 of the doubletree, this evener bar being pivoted at its middle to the tongue in any suitable or usual manner. Pivots supported upon the ends of the evener bar are the swingletrees 12, each of these swingletrees being alike in form. Each swingtree is formed to provide upper and lower walls and a front wall, the front edge wall being cut away at 13 at op-

posite ends for the insertion of traces. Extending through each swingtree and forming the pivotal axis thereof is a bolt 14, this bolt being square in section but having ro-
tative engagement with the upper and lower walls of the swingtree and mounted upon this bolt between the said upper and lower walls is a rectangular plate 15 which is ro-
tatable with the bolt. Mounted upon op-
posite corners of the plate 15 are the trace-
engaging bolts 16 and 17. The trace-engag-
ing bolt 16 extends forward and laterally
from the rear corner of the plate 15 and is
guided in its movement by a guide pin 18. 60
The extremity of the bolt is deflected so that
it will normally extend parallel to the front
wall of the swingtree and engage the eye
of a hook inserted through the opening 13.
The other bolt 17 extends from the forward
corner of the plate laterally through the cor-
responding guide 18 and is adapted to en-
gage the eye of the other hook a. Attached
to the plate 15 is a coiled spring 19 which
is also housed within the hollow whiffletree, 65
the other end of this spring being attached
to any suitable supporting member as for
instance the guide 18 on that side. It will
be seen that the tension of the spring will
be at all times exerted to cause the plate and
bolt to rotate in a direction to retract the
trace-engaging bolts 16 and 17. Mounted
upon the bolt 14 to rotate therewith is an
arm 20. There are two of these arms 20,
one for each swingtree. 75

Mounted upon the tongue 10 either rear-
ward or forward of the evener bar 11 is a
latch comprising the U-shaped bracket 21
through which the pin 22 passes. This pin
is formed with a collar 23 and a spring 24 95
surrounds it and bears against this collar
and forces the pin downward. A chain or
other flexible connection of any suitable
character may be connected to the eye at the
upper end of the pin 22 whereby the pin 100
may be drawn upward against the force of
the spring 24. Connected to each of the
arms 20 is a link 25. One end of this link
is angularly bent as at 26 to engage a per-
foration in the end of the corresponding arm 105
20, while the other end of the link is down-
wardly bent as at 27 and then extended to
form an eye 28 through which the pin 22 is
adapted to pass. When the pin 22 is in
place it engages both of the eyes and holds 110
both of the arms 20 in position to hold the
pivot bolt 14 and the plate 15 turned so as

to project the bolts 16 and 17 against the tension of the spring 19. If, however, the pin 22 is withdrawn from its engagement with the links the spring 19 will promptly 5 act to cause the retraction of the bolts. It will be obvious that this device remains set, that is, in the position shown in Fig. 5 at all ordinary times and that the traces are simply engaged with the whiffletree hooks 10 through the eyes of which the bolts 16 and 17 pass. The locking bolts 16 and 17 are projected, of course, by the arm 20 being held in the position illustrated in Fig. 1 by means of the link 25. While it is, of course, 15 preferable to use the trace-engaging hooks α with which the bolts engage, these trace-engaging hooks being the ordinary whiffletree hooks, yet it is obvious that the traces might be engaged directly with the bolts 16 20 and 17. By using trace or whiffletree hooks, however, the bolts 16 and 17 may be projected at all ordinary times and the draft animals engaged with the swingletrees or 25 whiffletrees in exactly the same manner that they would be engaged with the ordinary whiffletrees.

It will be seen that my device is mounted entirely upon the tongue of the wagon and that this combined horse detacher and whiffletree may be readily applied to any form of vehicle. It is also obvious that the latching device consisting of the parts 21, 22, etc., 30 may be readily applied either in front of the evener bar or rearward thereof, as found 35 most desirable according to the amount that the tongue extends rearward of the evener bar.

Having described my invention, what I claim is:

- 40 1. The combination with a draft appliance, of a whiffletree coaxing therewith, the whiffletree being hollow and having trace hook receiving slots at its ends, a pivot pin passing through the whiffletree and upon 45 which it is oscillatably supported, a member mounted upon the pin and extending in diametrically opposite directions therefrom and rotatable therewith, trace-hook engaging bolts having their inner ends connected 50 to said member at diametrically opposite points, the outer ends of the bolts coaxing with the trace hook engaging slots and being adapted to engage through trace hooks

disposed in said slots, a spring normally acting to urge said member to a position to 55 retract the bolts, an arm mounted upon the pin and rotatable therewith, a link on the end of said arm, and means for detachably engaging said link to thereby hold the trace-engaging bolts from retraction under the 60 influence of the spring.

2. The combination with a tongue, of an evener bar mounted thereon, hollow swingletrees mounted upon the ends of the evener bar and having trace-hook receiving slots, 65 a pin passing through each swingletree and pivoting it to the evener bar, a rectangular member mounted upon the pin and rotatable therewith, trace-hook-engaging bolts having their inner ends connected to said member 70 diametrically opposite each other, the outer ends of the bolts coaxing with the trace-hook engaging slots and being adapted to engage through trace-hooks in said slots, a spring normally acting to urge said member 75 to a position to retract the bolts, an arm mounted upon the pin, a link on the end of each of said arms, and means for detachably engaging said links to thereby hold the trace-engaging bolts from retraction under 80 the influence of the spring.

3. The combination with a tongue, of an evener bar mounted thereon, swingletrees pivotally mounted upon the ends of the evener bar, each of said trees being hollow, 85 a pivot pin forming the pivotal axis for each swingletree and extending therethrough, a plate rotatable with said pin and disposed within the swingletrees, trace-hook engaging bolts connected to diametrically opposite 90 points of the plate, a spring connected to the plate to urge its rotation in one direction to cause the retraction of said bolts, guides for the bolts, an arm mounted upon each pivot pin and rotatable therewith, and means for holding said arms in a bolt projecting position comprising links connected to said arms and having eyes, a U-shaped bracket, and a spring actuated pin disposed in said bracket and engaging said eyes.

In testimony whereof I hereunto affix my signature in the presence of two witnesses.

ABRAHAM KYDLAND.
